UNITED STATES PATENT OFFICE.

ASHTON G. STEVENSON, OF CHICAGO, ILLINOIS.

TYPE-SLUG-CASTING MACHINE AND PRODUCTS.

Application filed February 10, 1921. Serial No. 443,864.

To all whom it may concern:

Be it known that I, ASHTON G. STEVENSON, a citizen of the United States, and resident of Chicago, in the county of Cook and State of Illinois, have invented certain new and useful Improvements in Type-Slug-Casting Machines and Products, of which the following is a specification.

My invention relates to improvements in means for producing printers' type slugs or type bars and has special reference to attachments or appurtenances for use on what is commonly known as linotype and similar type bar casting machines, whereby printing slugs can be cast by the use of matrices other than those for which the machine is designed and adapted to produce printing slugs having faces much wider than the bodies of the slugs, in other words much wider than the width of the mold slot in which the bodies of the slugs are cast.

A particularly valuable feature of my invention is that it broadens the usefulness of the standard linotype machines by making them capable of producing printing slugs for printing display headlines, which heretofore have required the installation of special machines.

To arrange a standard linotype machine so that wide faced type slugs can be cast, in accordance with my invention, requires merely the substitution of what is known as a low mold for the standard height mold and then the withdrawal or lifting out of the way of what is known as the first elevator, and the introduction between the jaws of a solid or rigid holder or frame in which the matrices for producing the wide-faced printing slugs to be cast have previously been assembled and locked.

I preferably place in the machine a support having a shelf upon which this rigid frame is set between the vise jaws and providing a suitable backing by which the frame and the matrices are firmly held and backed up when the mold wheel is moved forward to press the mold against the matrices for the casting operation.

At the present time it is quite usual to install on the mold wheel of standard linotype machines which carry four molds, one mold which is lower than the rest by practically one-sixth of an inch. All of the changes for casting the wide-faced slugs to which this invention particularly relates, and for placing the machine back again in

normal slug-casting condition occupies less than a minute after the substitution, if such is necessary, of the low mold for the standard mold, and requires or necessitates no alteration of the several fine adjustments which it is necessary to preserve in such machines for accurate work.

My invention contemplates certain automatic registering features by which the line of matrices in the rigid holder shall be accurately registered with the mold slot.

A further feature relates to the production on the mold face of a continuation of the matrix contacting surface of the mold cap so that very wide faced printing slugs can be cast, having the body of the slug arranged beneath one lateral edge thereof and means for setting the holder on the shelf so that the lower sides of the letter matrices, openings or recesses shall be accurately aligned or registered with the lower side or bottom of the mold slot.

In the present practical development of the art there is in quite general use a system of producing type furniture or quad material on linotype and similar slug-casting machines, which involves the use of a so-called low mold, which is about one-sixth of an inch lower than the standard mold. Such a low mold is disclosed in my patent of the United States, No. 1,260,828.

This present invention makes use of such a low mold in connection with matrices having letter or matrix recesses deep enough to make up for the amount that the mold is less than standard height, which, in the matrices and mold involved is substantially one-sixth of an inch.

My invention will be more readily understood by reference to the accompanying drawings forming part of this specification, and in which:

Figure 1 is a fragmentary front elevation of a mold wheel and vise slot equipped with a matrix holder made in accordance with my invention;

Figure 2 is a rear view of the vise block and matrix holder, the mold wheel being removed;

Figure 3 is a fragmentary horizontal sectional view on the line 3-3 of Figure 2;

Figure 4 is a vertical sectional view on the line 4-4 of Figure 2;

Figure 5 is a sectional view similar to Figure 2 illustrating the manner of registering the matrix recesses with the mold slots

when the recesses are wider than those shown in Figure 4;

Figure 6 is a section similar to Figure 4 showing the means which I provide for extending the matrix contacting surface of the mold cap when extremely wide-faced slugs are to be cast.

Figure 7 is a fragmentary front view of the mold showing the filler bar or member 10 attached thereto;

Figure 8 is a perspective view of one of the matrices which I employ;

Figure 9 is a rear elevation of the matrix holding frame illustrating the means which 15 I employ, for clamping or locking matrices in the holder which are particularly adapted for making italic letters;

Figures 10 and 11 are fragmentary rear elevations of the holder illustrating the 20 alternate use of the matrix clamping means to properly clamp and hold italic matrices and ordinary matrices;

Figure 12 is a rear elevation of the matrix holder and supporting member, illustrating one means for causing the frame to set the matrices in proper registry with the mold slot;

Figure 13 is a fragmentary elevational view similar to Figure 2 illustrating a modified means for locking the matrices in the rigid holder.

Figure 14 is a fragmentary horizontal section on the line 14—14 of Figure 13;

Figures 15 and 16 are perspective views 35 of the wedges made use of in the locking device shown in Figure 13;

Figure 17 is a diagrammatic plan view illustrating the operation of wedging the matrices in the holder;

Figure 18 is an end elevation of the holder and its support;

Figure 19 is a fragmentary vertical longitudinal section on the line 19—19 of Figure 18;

Figure 20 is a vertical cross-section of a low mold shown in combination with a recessed slide;

Figure 21 is a fragmentary horizontal section of the mold shown in connection with 50 a line of matrices and a pot mouth; and

Figure 22 is a detail vertical cross-section of a printing slug having an overhanging printing part and a support slug such as is produced by the devices shown in Figure 20.

55 In said drawings, 1 represents the mold wheel of the usual form employed on linotype and similar type slug casting machines, and 2 represents a vise block which is mounted in front of the mold wheel and is

60 adapted to be secured rigidly to the frame of the machine by suitable clamping screws or bolts 3. The vise block carries a pair of vise jaws 4 and 5 which are movable from and toward each other in the vise block 2 by

65 suitable means which it is not necessary to

describe in relation to the present invention. These vise jaws are arranged adjacent to the face of the mold and are adapted, as ordinarily used, to receive between them an assembled line of matrices, and are adapted to 70 clamp the line of matrices tightly together in relation to the mold for holding the matrices during the casting operation. The mold, which is carried by the mold wheel 1, consists of a base or lower part 6 and a cap 75. These two parts are spaced apart by a liner 8 which is cut away between its ends to provide a mold slot 9 and has projections 10 at its end for properly spacing the two parts of the mold apart, said parts being 80 adapted to be held clamped tightly together by screws 11 at their ends. The mold slot 9 extends the length of the mold between the inner edges of the spacing projections 10 and provides a mold slot substantially the 85 length of the mold. In the use of such a mold in a linotype or a similar machine there is provided a mouth piece 12 connected with the pot in which the molten metal is contained and which is adapted to contact 90 with the rear face of the mold and is provided with metal delivery openings adapted to register with the mold slot 9 and through which the molten metal is forced into the mold slot, for the production of the printing slug.

In what are known as standard height molds and the matrices which are used therewith for the production of what are known as standard linotype slugs, the mold 100 from its rear face 14 as shown in Figure 4 to its forward face 15, is substantially the height of the slug to be cast, the recess in the standard matrix being but a few hundredths of an inch deep. In consequence 105 of this the mold slot 9, from its bottom surface 16 to its top surface 17 corresponds substantially with the width of the face of the slug to be cast. This precludes any possibility of producing narrow bodied wide 110 faced slugs, the overhanging parts of which are of substantial thickness or height.

In the use of the standard linotype machines there is provided a vertically movable matrix holder or elevator which slides up and down on the vise block 2 in guides 18 and when I arrange such a machine for use in accordance with my present invention I remove such elevator by lifting up 115 its matrix holding part out of the way so that I can readily arrange the vise block and vise jaws for co-operation with the parts which I provide for use in accordance with my invention.

The ultimate object of my invention is 120 the production of very wide faced printing slugs on the linotype machine by the use of matrices which are illustrated at 125 (Figure 8) each of which is provided with a relatively deep recess or matrix opening 130

20, in the bottom of which is the depression which is adapted to produce the letter or character desired.

It will be clear from Figures 4, 5, and 6 that when such a matrix is arranged in front of the mold, or rather when a line of such matrices is arranged in front of the mold, the deep recesses 20, in addition to the depth of the slot 9 from front to the back of the mold can be arranged to produce a printing slug of standard height; in other words the mold from front to back, that is, from the surface 14 to the surface 15 marked "A" in Fig. 6, is reduced in dimension below the standard dimension by the amount of the depth of the recess 20, which is greater than the depth of the ordinary standard matrix, that is, substantially one-sixth of an inch. It will also be understood from Figures 4, 5 and 6 that when such a line of matrices is held in position before the mold and in proper relation to the mold slot, a wide faced slug can be produced in accordance with the width of the recesses in the several matrices, and that the body of the slug 22 will be determined by the dimensions of the mold slot 9, and that the under side 23 of the overhanging part 24 of the slug will be produced by the front face 15 of the mold, and will thus be a definite height above the bottom 25 of the slug 22.

In the construction or form of vise jaws 4 and 5, which are commonly employed, there is provided a horizontal supporting surface 26 arranged about five-eighths of an inch below the bottom surface 16 of the mold slot and I make use of this wall or surface for supporting the matrix holding and clamping devices which I employ for properly positioning and holding the matrices 19 in relation to the mold slot 9. These devices consist of a supporting or backing block or member which is adapted to be supported on the two vise jaws 4 and 5, the vise jaws having been separated substantially to their full extent before this member is placed in position, this member having a plain forward face 28 which contacts with the rear edges of the matrices and this block being backed up or held rigidly in the vise block 2. It serves in turn to back up or hold rigidly the matrices when, in the casting operation, the mold wheel with its mold, is moved forward into pressure contact with the faces of the matrices so as to prevent the escape of the liquid metal between the forward face of the mold and the contacting faces of the matrices.

I provide this block 27 with a forwardly extending shelf 29 at its lower end which extends substantially the full length of the block, and upon which I position or mount a rigid frame 30, which is adapted to receive, clamp and hold the matrices in an assembled line for placement before and in contact with the mold. The frame 30 is rectangular in shape, having a top bar 31, a bottom bar 32 and end connecting bars 33 and 34 providing a longitudinal slot or opening 35 for the reception of the matrices 19. The matrices 19 are entered into the slot 35 from the rear and are provided with top and bottom projections 36 at their rear edges which enter into longitudinal grooves 37 in the upper and lower bars of the holder to position the several matrices with their front faces in the plane of the front face of the holder for proper contact with the front face of the mold. For setting the frame 30 at a height to cause the lower edge of the matrix openings 20 to register accurately with the lower or bottom 16 of the mold slot 9, I arrange means for setting the frame 30 at the right height above the shelf 29. In the form illustrated in Figures 4, 5 and 6 this means consists of a horizontal plate 39 upon which the frame 30 sets and the forward edge 40 of which extends forwardly from the face 38 of the frame and is adapted to enter into a horizontal slot or groove 41 in the face of the base of the mold, which slot is arranged parallel with the mold slot and extends substantially the length of the base. The upper wall 42 of the slot 41 is accurately in parallelism with the bottom wall 16 of the mold slot, and I provide means for forcing the plate 39 upwardly into contact with the upper wall 42, whereby the top supporting surface of this plate is set accurately in relation to the mold slot and the lower bar 32 of the frame, together with the size of the matrices, is so arranged that when the plate 39 is in tight contact with the upper wall 42 of the slot 40 the matrices are accurately registered with the mold slot, the lower walls of the recesses 20 being in accurate registry with the lower wall of the mold slot as shown in the several figures. For automatically forcing this plate 39 into such tight contact with the upper wall 42 of the groove 40, I provide an automatic wedging device below the plate supported on the shelf 29.

For this purpose I make the upper surface 43 of the shelf 29 inclined upwardly and rearwardly and I provide a wedging member 44 supported on this shelf and having an upper horizontal surface 45 upon which the plate 39 rests. This wedging member 44 normally rests at the lower limit of its movement on the inclined surface 43, being limited in back and forth movement by guide pins 46 which are rigid with the plate 39 and extend downwardly through the wedging member 44 and the shelf 29, the wedging member being properly slotted to permit its back and forth movement. For pushing the wedge rearwardly or up the incline to lift

the plate 39, I provide push pins 47, one near each end of the wedge and extending horizontally through the wedge, the outer ends of these pins being adapted to contact with the 5 face of the mold as the mold approaches the matrix holding device and to push the pins back through the wedge. The wedge is provided with suitable openings 48 surrounding the pins 47 for containing compression 10 springs 49, which are adapted to be compressed rearwardly by collars 50 rigid with the pins 47. This arrangement permits the pins to be pushed clear into the wedge and to provide a wedging pressure on the wedge to 15 force the wedge rearwardly and upwardly on the inclined surface 43 and lift the plate 39. The springs 49 bear against the rear surface of the openings 44 in the wedge block and thus produce the wedging pressure. If the 20 plate 39 contacts properly with the upper wall of the groove 40 before the mold properly contacts with the matrices, further movement of the mold toward the matrices simply further compresses the springs, the pins being 25 yieldingly permitted to recede into the wedging block.

For properly positioning the lines of matrices which have wider recesses than those shown in Figure 4, I provide suitable 30 removable fillers or liners 51 of proper dimensions for lifting the frame sufficiently to cause the lower sides of these wider recesses to register with the lower wall 16 of the mold slot 9, as best shown in Figure 5.

35 In Figure 12 I have shown another simple means of causing the recesses in the line of matrices to properly register with the mold slot. This means consists of vertically adjustable screws 29" having their lower ends 40 projecting from the lower ends of the end bars 33 and 34, of the frame 30 and adapted to be adjusted in height relatively to the frame and their lower ends adapted to contact with the shelf 29' which takes the place 45 of the wedging shelf 29 hereinbefore described. It is obvious that the shelf 29' need not have a wedging surface and the screws 29" can be adjusted sufficiently to properly register matrices having different dimensions 50 of recesses. These screws 29" are adapted to be locked in place by suitable set screws 52.

55 For the purpose of casting slugs having exceedingly wide faces, as shown at 54, Figure 6, I provide a filler bar 55 for extending the front face 15 of the mold upwardly a sufficient distance so that the upper part of the matrices may be closed tightly upon the mold. In Figure 6 I have illustrated the matrices 56 having exceedingly wide recesses 60 which extend above the narrow lip or edge 57 which is commonly produced upon the caps of such molds. The bar 55 fills in between the forward surface 58 of the cap above the projection 57 and the adjacent face 65 of the matrices. The wide face 54 of the

slug extends over and beyond the lower edge of the bar 55. For holding this bar in place on the cap I provide downwardly extending projections 59 at its ends. These projections 59 are thick enough to make up for the reduction in thickness of the mold and are secured to the liner by screws 60.

70 For properly registering the frame 30 with the blocks 27, the forward face of the block is provided with vertical slots or guide grooves 75 61 at its ends and the frame is provided with vertical bars 62 which slide down in the vertical slots and fit therein, and the forward face of the frame 30, that is the face which contacts with the mold, is provided with vertical 80 flat bars 63 at its ends, of even thickness with the projections 59 at the ends of the filler bar 55, these bars 63 close the ends of the mold slot as best shown in Figure 3, to prevent the escape of the hot metal at these points. It is 85 obvious that in place of the projection 59 on the filler bar 55, separate projections or plates could be used when it is not desired to use the filler bar 55 and between which the bars 63 are placed to place the matrix frame end- 90 wise in relation to the mold slot.

95 For locking the line of matrices in the holder frame I provide a simple wedging device comprising a wedge 64 (see Figure 11) at one end of the matrix slot 35 which presents an inclined surface 65 toward the line of matrices, and is carried by a vertical screw 66 extending upwardly through the upper bar 31 of the holder frame and provided on its upper end with a thumb nut 67 100 by which the wedge can be drawn upwardly to tighten the matrices in the holder. Between the wedge 64 and the matrices I provide a complementary wedge block 68 provided with an inclined surface 69 at the 105 same angle as the wedging surface of the wedge block 64 and with an opposite surface 70 which is arranged vertically in the holder or at right angles to the top and bottom bars of the holder, and adapted to contact with the matrices 19 and bind them tightly in 110 the frame when the wedge 64 is drawn upwardly.

115 There are in use at the present time many sets of matrices similar to those already described, but arranged on an incline, as shown at 71, (Figures 9 and 10). These matrices are particularly adapted for producing italic letters and are adapted to be arranged in parallel relation when placed in 120 a line of matrices and all at the same angle, as best shown in said figures. In making my wedging block 64 and the co-operating block 68, I make the inclined or wedging surfaces thereof on the same angle as the 125 angle which is used in producing the italic matrices 71, and when it is desired to bind a line of the inclined matrices 71 in the holder, I place the block 68 at the opposite 130 end of the slot 35 of the holder and arrange

the line of matrices between the opposed inclined surfaces 69 and 65 of the co-operating block 68 and the wedge 64, and I am thereby enabled to firmly and tightly clamp 5 the line of inclined matrices in the holder by drawing the wedge 64 upwardly by means of the screw 66 as in the former instance.

Having equipped a mold wheel with one 10 of the low or furniture molds it will now be apparent that in order to change or adjust the machine for casting these wide faced printing slugs by the use of matrices such as have been described, it is only necessary to take the elevator of the machine out 15 of the way to drop the backing block 27 into position and having assembled the matrices in the holder 30 for producing the line desired, to place this in position in the machine 20 on the shelf 29 and to close the mold against the opposed edges of the line of matrices, taking care, of course, to arrange liners below the same if such be necessary in 25 order to cause the lower edges of the recesses of the matrices to properly register with the lower wall of the mold slot.

The depth of the furniture mold is made a standard of .759 inches in order that electrotype plates which are .159 inches will be 30 supported with their printing surfaces at a height of .918 from the base when placed on such furniture, this being the standard printing height of printing type and linotype slugs and such like printing material. 35 In order to be able to produce suitable slugs or quad supports for the overhanging printing slugs produced by the matrices illustrated and which have a standard matrix depth of recess of .153 inches, I provide 40 means in combination with my standard furniture mold for adding .006 of an inch to the height of furniture. This I accomplish by providing slides which are known as matrix slides for closing the mouth 45 of the mold slot which slides are recessed to a depth of .006 of an inch so that when these slides are used for producing furniture, the height of the furniture is .765 inches instead of .759 inches and when the 50 overhanging parts which are .153 inches thick are supported on this special furniture their printing faces are held at the standard height of .918 inches above the base. This results in a very important advantage in the 55 production of such overhanging printing slugs, viz: the separation or lifting up of the lower edge of the bodies of the slugs from the supporting plate or in other words above the bottom of the supporting furniture. 60

As best illustrated in Figures 20 and 22 inclusive, the pot mouth 12 is provided with a row of small discharge openings 72 and with vertical air outlet grooves 73 provided 65 in the flat mold contacting surface of the

pot mouth 12 between the holes 72. When a slug is cast the type metal produces small protuberances on the bottom edge 25 of the slug as the metal solidifies to some extent in the discharge holes 72 and the metal 70 usually fills the air discharge grooves 73 forming slight transverse ribs on the bottom edge 74 of the slugs. It is necessary to take off these ribs and protuberances so as to make the slug perfect. This trimming 75 or cutting is commonly accomplished by means of a knife in the casting machine which contacts with the bottom of the slug. It has been my experience that this knife is not apt to be well taken care of as it 80 is back in the machine and is not readily removable for sharpening, with the result that the trimming operation is not usually perfectly accomplished. At other times, the slug, under the trimming operation, the 85 knife being dull, is pushed forwardly or partly out of the slug mold with the result that the excrescences on the bottom of the slug are not entirely removed. Under still other conditions some of the particles removed may adhere to the slug. Under such conditions unless a space is provided to receive these protuberances or particles the slugs would not be properly positioned. I avoid these difficulties by the extra height 90 that I arrange to make the supporting slug in combination with the low mold which produces the vertical portion of the printing slug, and which provides a space below the edge 25 of the printing slugs when they 95 are assembled in the printing form of .006 of each inch so that in such assembly of these members the overhanging printing parts of these slugs may rest firmly down upon the upper surfaces of the extra height 100 supporting slugs and with their printing surfaces in the printing plane of the printing form of which they form a part.

The recessed slide is illustrated at 82 held in a slide block 83 and provided with a 110 shallow recess 84 in its face which is presented to the mold slot.

In Figures 13 to 19 inclusive I have illustrated another wedging means for locking the matrices 19 in the rigid holder. In 115 this form of my device I provide a rigid holder 75 similar to the holder 30 but with ends which are much thinner as I eliminate the vertically adjusted wedge with its screw adjustment and substitute two wedges 76 120 and 77 which are adapted to be placed in wedging engagement by a relative horizontal rather than a relative vertical movement. In vertical section, as best shown in Figures 15 and 16, the wedges are similar 125 in section to the shape of the matrices 19 and are adapted to be placed wholly within the T shaped opening provided for the matrices in the holder 75. The reduction of the end parts of the holder results in 130

a longer space for containing matrices and consequently in a longer possible printing slug. The wedges 76 and 77 are entered into the opening in the holder between the line 5 of matrices 19 and one end of the frame 75 and in order that the wedges may be entered wholly into the frame so that they will not project to prevent the support 27 properly holding the matrices against the 10 mold, I provide a yielding abutment in the form of a spring member 78 which as shown I preferably arrange centrally of the line 15 of matrices in vertical position at the end of the frame 75 and secured at its upper and lower ends to the top and lower bars of the frame. The middle part of this member is bowed or sprung inwardly toward the wedges and as the wedge is pushed in to tighten the line of matrices in the holder 20 the spring yields back sufficiently to permit the wedge to be pushed clear in. The force of the spring is sufficient, even tho it may not be sprung clear back, to firmly hold the line of matrices. To facilitate the entrance of the thin edge 79 of the wedge 77 between the thin edge 80 of the wedge 76 and the next adjacent matrix 19 I taper off the edge 80 as shown at 81 to provide an open crack to receive the entering edge 25 87 of the wedge 77. This holder 75 is adapted to be held on a support 27 similar to that already described and to be likewise registered with the mold slot.

It will now be apparent that the devices 30 which I make use of to thus extend and to widen the capacity and usefulness of the line casting machines are extremely simple in themselves, that they do not require the readjustment of the several parts of the 35 machine which oftentimes occupies considerable time, and that it is only necessary, as explained above, to remove one part of the machine which is readily removed and place in position two main parts of the device.

As it is obvious that many modifications 40 of my invention will readily suggest themselves to one skilled in the art I do not limit or confine my invention to the specific de-

tails of construction or association of parts and mechanisms, herein shown and described.

I claim:

1. The herein described printing slug having a narrow body and an upper printing part extending on one side thereof, in combination with a supporting slug adapted to receive the overhanging part of the printing slug and of such relative height that the lower edge of the printing slug is maintained above the lower surface of the supporting slug.

2. A printing slug having an overhanging printing surface, in combination with a supporting slug adapted to be arranged beneath same, the relative height of the supporting slug and the body of the printing slug being such that the lower edge of the body is lifted clear of the surface upon which the supporting slug rests.

3. A printing slug having an overhanging upper part, in combination with a supporting slug of such relative height that the printing surface of the printing slug is maintained at standard printing height and the lower edge of its body is maintained clear of the support upon which the supporting slug rests.

4. A printing slug having an overhanging part and a body having parallel sides, the total height of the printing slug being slightly less than standard printing height, in combination with a supporting slug adapted to be arranged beneath overhanging part of the printing slug and to hold the body of the printing slug above the support upon which the supporting slug rests.

5. A printing slug having a relatively thin body part and a top laterally extending portion adapted to rest upon a quad block, the body portion of the slug being of less height than the quad block upon which the slug is adapted to rest.

Signed at Chicago, Illinois, this 7th day of February, 1921.

ASHTON G. STEVENSON.
